UNITED STATES PATENT OFFICE.

ALLIE R. WELCH AND FRED STIMSON WELCH, OF PONTIAC, MICHIGAN.

DESIGN FOR AN AUTOMOBILE-BODY.

No. 37,693.

Specification for Design.

Patented Nov. 21, 1905.

Application filed May 29, 1905. Serial No. 262,939. Term of patent 14 years.

To all whom it may concern:

Be it known that we, ALLIE R. WELCH and FRED STIMSON WELCH, citizens of the United States, residing at Pontiac, in the county of Oakland and State of Michigan, have invented a new, original, and ornamental Design for Automobile-Bodies, of which the following is a specification, reference being had to the accompanying drawing, forming part thereof.

The figure is a perspective view of an automobile-body showing our new design.

We claim—

The ornamental design for an automobile-body, as shown.

ALLIE R. WELCH.
FRED STIMSON WELCH.
